UNITED STATES PATENT OFFICE.

CHARLES L. HENNING, OF CHICAGO, ILLINOIS.

TOWEL-RACK.

1,186,984.

Specification of Letters Patent. Patented June 13, 1916.

Application filed February 8, 1915. Serial No. 6,783.

To all whom it may concern:

Be it known that I, CHARLES L. HENNING, a citizen of the United States, residing at Chicago, in the county of Cook and State 5 of Illinois, have invented certain new and useful Improvements in Towel-Racks, of which the following is a description.

My invention belongs to that general class of devices known as towel racks, and relates 10 particularly to a device for containing a plurality of individual towels of the desired size, which towels are locked in the rack so as to prevent the unauthorized removal of the same; and consequent loss, by theft or 15 otherwise.

My invention has among its objects the production of a device of the kind described, that is simple, convenient, efficient, durable, and satisfactory, for use wherever found applicable.

It has also among its objects the production of a device particularly suitable for 20 towel supply houses furnishing regular service, wherein the desired number of towels 25 are regularly furnished to the consumer, usually the one supplying the towels keeping them laundered and renewed. Likewise, the towels are confined to the particular use 30 intended, and cannot be removed for other purposes, thereby unduly soiling or ruining the towels.

Other objects of the construction will appear to those skilled in the art to which the invention belongs.

To this end my invention consists in the 35 novel construction, arrangement and combination of parts herein shown and described, and more particularly pointed out in the claims.

In the drawings, wherein like reference 40 characters indicate like or corresponding parts; Figure 1 is a front elevation of my device, a portion cut away to more clearly show the construction; Fig. 2 is a perspective view of one part of the preferred clamping member; Fig. 3 is a similar view of another coöperating part; Fig. 4 is a similar 45 view of another coöperating part; Fig. 5 is a sectional view through the device, taken substantially on line 5, 5 of Fig. 1; Fig. 6 is a sectional view taken substantially on line 6, 6 of Fig. 5, and Fig. 7 is a view in elevation of the locking mechanism, taken 50 substantially on line 7, 7 of Fig. 6.

Before entering into a detailed description 55 of the parts it may be said that the de-

vice comprises, in the preferred form, a suitable case or cabinet, in which may be locked a suitable towel container or clamp, in which the desired number of towels may be securely locked. The casing may be of any preferred style and of any suitable material. As shown, it consists of a back 1, and suitable sides 2, the front being preferably closed by a door 3, hinged as may be found most convenient, preferably to one of the sides of the case. I have shown only a few towels in the case, and these are of such length that they may be clamped or locked in the middle, and both ends used. While 60 the parts are ordinarily made to fit the particular size of towel desired, the same will carry any smaller towel regardless of the size, and clamp the same at the ends or between the ends.

The towels are secured in a clamp, comprising parts 10, 15 and 20. Part 10 is substantially U-shaped, being formed with offset ends 11, preferably perforated in one or more places on each side, as at 12, and is provided with supporting pins or extensions 14, one on each end. Part 15 is formed with an offset at 16 between the ends, and with a lug or extension 17 arranged to engage the part 10 in one of the holes 12. It is also provided with a lug or extension 18, or the equivalent, and with a part 19, or its equivalent, having a hole therethrough. The part 20 is formed with a lug or extension 21 at 75 one end for engagement with the hole 12 at the opposite end of part 10, and is also formed with apertures 22 and 23 for the reception of the parts 18 and 19 on part 15. The parts assembled are most clearly shown in Fig. 6. The towels are clamped between part 10 and the parts 15 and 20, and securely locked in position by a padlock 38, or equivalent sealing or locking device, engaging in the part 19 on the outer side of part 20. The particular holes 12-12 engaged by the extensions 17 and 21 depend upon the number of towels to be carried, it being understood that the clamp may be constructed to receive any desired number of towels, as for example, 75, 100 or more. By offsetting the parts 15 and 20, as most clearly shown in Fig. 6, when the towels are positioned, and the parts sprung and locked into position, the towels are substantially clamped throughout their width, and secured in place 100 in such a manner that it is practically impossible to remove them without cutting the 110

towels. Likewise, owing to the engagement of the ends, in addition to the pins or lugs 17 and 21 with the parts or extensions 11, the clamping members 15 and 20 cannot be drawn down or moved transversely edge-wise, so as to release the towels, although the parts may be removed without difficulty, and in but a moment's time when unlocked.

Where the towels are arranged to be used at both ends, as shown in the drawings, they are clamped substantially in the middle, and all of the ends hung either to the front or to the back, as shown to the back. The user then draws a towel down, for example the end 5 at the front, and wipes his hands or face. The next user draws one end of towel 6, etc. This is continued, until the other end of the towel is used, so that each clean towel may be used twice. It will be particularly noted that the thickness or width of the clamp separates the soiled and clean towels, and under no circumstances can any but the lower or inner clean towel possibly contact with the soiled towels.

25 The towel may be secured or locked within the cabinet, or its equivalent, in any desired manner. As shown, I preferably provide brackets 24 and 25, arranged to engage with the lugs 14 of part 10, and suitably support the same. As shown, bracket 24 is secured in place by screws 28, it being understood that any other securing means may be employed. The parts are both preferably offset as at 26 at the lower end, so that the ends of pins 14 do not bind on the cabinet. To permit the ready removal of the clamp only by one authorized to remove it, I detachably secure bracket 25 to side wall 2, and provide simple means for locking it in place. As shown, a plate 29 is secured to the side walls by screws 30, or the equivalent, the same being provided with lugs 31 for guiding the part 25 and maintaining it in position. Part 25 is formed with an extending lug or post 32 adapted to extend through a suitable opening or hole in plate 29, and be engaged by a locking member 33. In the construction shown, member 33 is arranged in the form of a cam, and is adapted to engage in a slot or groove in the pin 32. A stop 34 is also provided for limiting the movement of the cam locking member 33. Member 33 may be shifted or partially rotated to release pin 32 in any suitable manner, a post 35 being provided for this purpose. A key (not shown) or its equivalent, may be inserted through the opening 36, so as to engage the post 35, and rotate the cam to release the parts. While any equivalent locking mechanism may be employed, that shown is extremely simple and inexpensive, and cannot be operated by pliers, or the like, to release the clamp.

65 In use, assuming that all the towels in the cabinet have been soiled, and it is desired to

replenish the same, the supply man inserts his key through the opening 36, and unlocks the bracket 25, so that the clamping member may be removed and a new one provided with the desired number of clean towels inserted. The bracket is then again locked in place, securing the towels in the cabinet. The towels may be placed in the clamps at the supply house or at the laundry, as the case may be, and at this time they may be counted. This facilitates the delivery of a clean supply, avoids mistakes, and affords a convenient method of carrying the towels in the wagon. The door 3 normally covers the soiled towels so that the device is not unsightly. If the towels are hung with the clean ones at the front, the soiled towels may be thrown to the back, where they are in addition to the door covered and hidden by the clean supply. It will be noted that while the clamping member is shown extending straight, it may be rocked in one direction or the other about its pivots, depending upon which side the greater number of towels are hung. In other words, if the dirty towels are carried at the front, as shown, the clamping members will be slightly tipped, as the number of dirty towels overbalances the clean ones, facilitating the grasping and pulling over of the clean towels.

Having thus described my invention, it is obvious that various immaterial modifications may be made in the same without departing from the spirit of my invention; hence I do not wish to be understood as limiting myself to the exact form, construction, arrangement or combination of parts herein shown and described, or uses mentioned.

What I claim as new and desire to secure by Letters Patent is:—

1. In a device of the kind described and in combination, a suitable cabinet, a clamping member detachably secured therein, and means for locking said clamping member in place, said clamping member comprising a U-shaped part, a coöperating part having one end secured to one extending leg of the U, and the opposite end extended past the center of the first member, a second coöperating member having one end secured to the other leg of said first mentioned member with the opposite end extended past the center thereof, and means for locking said coöperating parts in operative positions.

2. The combination in a device of the kind described of a U-shaped member provided with means at each end for supporting the same, a coöperating clamping member arranged at one end for engagement at one side of said U-shaped member, a second coöperating part arranged to engage the other side of said U-shaped member, one part arranged to engage with the other intermediate the ends thereof, one of said parts provided with a slot therein and the

other with an extension arranged to pass through said slot, and means for engaging said extension and locking the parts against separation.

5 3. In a device of the kind described and in combination, a suitable cabinet, a towel clamping member arranged therein, and means for detachably supporting said clamping member and locking the same in operative position, comprising a bracket secured to one side of said cabinet and arranged to carry one end of said clamping member, and a similarly formed bracket arranged at the opposite side of the cabinet, and arranged 15 to engage the other end of said clamping member, and means for locking said last mentioned bracket to the cabinet wall, comprising a lug carried by said bracket, and key-controlled means carried 20 by said side wall for engaging the said lug.

4. The combination in a device of the kind described of a suitable cabinet, towel supporting and securing means arranged therein, means for securing said securing means in place, including a plate secured to the 25 side wall of said cabinet, said plate provided with an opening therethrough, a bracket having a part extending through said opening, a locking member arranged to engage said part on the side of said plate 30 opposite said bracket, and means for operating said locking member from the exterior of the cabinet.

In testimony whereof, I have hereunto signed my name in the presence of two 35 subscribing witnesses.

CHARLES L. HENNING.
